(57) **CLAIM**

We claim the ornamental design for diamond-design window shutter, as shown and described.

DESCRIPTION

FIG. 1 is a perspective view of diamond-design window shutter, embodying the design of the present invention, in use with an identical optional opposing diamond-design window shutter shown in phantom; the broken line showing of environmental window structure is for illustrative purposes only and forms no part of the claimed design.

FIG. 2 is a front elevational view thereof;

FIG. 3 is a rear elevational view thereof;

FIG. 4 is a left side elevational view thereof, the right side elevational view being a mirror image thereof; and,

FIG. 5 is a top plan view thereof, the bottom plan view being identical thereto.
